UNITED STATES PATENT OFFICE.

ALPHONSO H. COBB, OF ASHEVILLE, NORTH CAROLINA.

DESIGN FOR A GARMENT-FASTENING HOOK.

SPECIFICATION forming part of Design No. 31,786, dated November 7, 1899.

Application filed October 16, 1899. Serial No. 733,827. Term of patent 14 years.

To all whom it may concern:

Be it known that I, ALPHONSO H. COBB, a citizen of the United States, residing at Asheville, in the county of Buncombe and State of North Carolina, have invented and produced a new and original Design for a Hook for Garment-Fastenings; and I do hereby declare the following to be a full, clear, and exact description of the invention, such as will enable others skilled in the art to which it appertains to make and use the same.

My design consists, essentially, of a hook for a garment-fastening comprising the following essential characteristics: A pair of relatively long spaced parallel members having their corresponding ends curved inwardly in the substantial form of circles adjacent to each other and lying in the same plane with each other and with the two said parallel members, the opposite ends of said parallel members extending at right angles toward each other and curved from the plane of the said parallel members, contacting and extending backward a relatively short distance in a plane parallel to the said spaced members and curving suddenly toward the plane of the said spaced members, terminating in a still shorter retroverted portion lying in a plane between the plane of the two spaced parallel members and the contacting members, substantially as shown in the accompanying drawings.

In the accompanying drawings, which illus-

trate my design, Figure 1 represents a top plan view of the hook. Fig. 2 represents an end view of the same seen from the left in Fig. 1. Fig. 3 represents a side view of the same as looking toward the top of the sheet in Fig. 1.

A A represent the relatively longer spaced parallel members having their corresponding ends curved into the form of circles at A⁰ and connected at their opposite corresponding ends with the portions A' at right angles thereto and curved upwardly and making contact at A².

A³ A³ represent the relatively short contacting portions lying in a plane above the plane of the members A A and curving suddenly at A⁴ toward the plane of said members A A, terminating in the still shorter retroverted portion A⁵, lying in a plane between that of the portions A³ and A. The end of the retroverted portion A⁵ is somewhat flattened and is rounded at its extreme end and its upper side, as shown, being flat upon its lower side.

What I claim as my invention is—

The design for a garment-fastening hook, substantially as shown and described herein. 60

In testimony whereof I affix my signature in presence of two witnesses.

ALPHONSO H. COBB.
